P. L. MARKEY

NECKTIE HOLDER

Filed Sept. 15, 1924

Inventor.
Peter L. Markey,
By Sprinkle & Smith
At this

UNITED STATES PATENT OFFICE.

PETER L. MARKEY, OF CHICAGO, ILLINOIS.

NECKTIE HOLDER.

Application filed September 15, 1924. Serial No. 737,669.

To all whom it may concern:

Be it known that I, PETER L. MARKEY, a citizen of the United States, residing at Chicago, in the county of Cook and State of Illinois, have invented certain new and useful Improvements in Necktie Holders, of which the following is a specification.

This invention relates to a necktie holder.

One of the objects of the present invention is to provide a generally improved form of necktie holder which is constructed of a thin flat, flexible piece of metal occupying a minimum amount of space between the band of the collar and the collar proper.

15 A further object of the invention is to provide an improved means in the form of a supporting band which can be easily and readily attached to or detached from the necktie holder proper and be adjusted with respect to the holder so that the height of the knot in the tie may be adjusted with respect to the holder.

A still further object of the invention is to provide an improved construction of a necktie holder and locking means therefor whereby ample means are afforded for firmly gripping the necktie holder and operating the latch mechanism in securing or removing the necktie holder from the collar button.

30 A still further object of the invention is to provide an improved necktie holder in which the tie or knot supporting band is mounted on the holder in a manner to eliminate any bulkiness at the point where the band is detachably secured to the holder.

A still further object of the invention is to provide a novel and improved means co-operating with the collar button and necktie holder for clamping the necktie holder in 40 position on the collar.

Referring to the drawings, Fig. 1 is a front elevational view of my improved necktie holder.

Fig. 2 is an enlarged fragmentary front elevational view of the latch mechanism showing the shank of the collar button in cross section.

Fig. 3 is an enlarged fragmentary front elevational view showing my improved 50 clamping mechanism.

Fig. 4 is a cross sectional view taken on the lines 4-4 in Fig. 3.

Fig. 5 is a cross sectional view taken on the lines 5-5 in Fig. 2.

55 Fig. 6 is a top plan view of my improved necktie holder showing the relative position

of the knot supporting band with respect to the holder when mounted thereon.

Fig. 7 is a front elevational view of my improved tie supporting band.

Figs. 8 and 9 are front and side elevational views respectively of the fork member of my improved clamping device, and

Figs. 10 and 11 are front and side elevational views respectively of the camming member of my improved clamping device.

The herein described invention is directed to improvements over the invention shown and described in my Patent No. 1,460,725 of July 3, 1923, and also over my Patent No. 1,499,389 of July 1, 1924.

The present invention is directed to an improved necktie holder construction which is adapted to detachably support ties that are knotted in a more or less permanent form, that is to say, after once the new tie has been knotted it is not necessary to untie the knot in order to remove the tie from the holder and substitute a different one. The principal objection to re-forming on each occasion that the tie is mounted on the holder is that by this repeated tying and untying the knot in the tie, the material which goes to make up the tie becomes wrinkled and creased and in some instances worn and distorted so as to give the same a shabby appearance. With the present construction the life of the tie is enhanced to a considerable degree and the time required for mounting and removing the tie is reduced to a minimum.

In the drawings, I have shown my improved necktie holder comprising a main body portion 15 having outwardly and upwardly curved arms 16. Formed integrally with the main body portion and arm 16 is a forwardly positioned portion 17 which is bent over as shown at 18 to a position parallel with the main body 15 so as to form substantially a casing 19 therebetween for the purpose of encasing and protecting a latch 20 which is pivoted at 21 to the portions 15 and 17. Each of the portions 15 and 17 are slotted as shown at 22. This slot 22 in the holder is adapted to receive the shank 23 of the collar button 24. The necktie holder is locked on the collar button 24 by the pivoted latch 20 which is provided with a plurality of notches 25 on one side of the latch bar and permits the holder to be adjusted with respect to the collar button so as to properly support the tie on the collar.

The latch bar 20 is provided with a downwardly extending portion or tail 26 having its lowermost end curved in the form of an eye 27. The eye 27 is adapted to have 5 mounted and secured therein a spring 28 which has its upper end secured to the holder as shown at 29 and has a portion intermediate its end engaging a lug 30 secured to or formed as an integral part of the main body 10 portion 15. By this arrangement the spring 28 exerts a resilient pressure on the lower end 28 of the latch bar 20 and thereby resiliently presses the latch bar 20 transversely of the slot 22 in the tie holder. The eye 27 formed 15 on the tail portion 26 of the latch bar 20 affords a very convenient means for actuating the latch bar in disengaging the bar from the shank 23 of the collar button. In order to provide means whereby the necktie 20 holder may be conveniently gripped by the thumb and forefinger while the middle finger is actuating the tail portion 26 of the latch bar 20 I have provided forwardly rolled 25 portions 31 which are formed integrally with the portion 17 of the holder adjacent the lower end thereof. By this arrangement it will readily be seen that the thumb and forefinger may firmly grip these rolled portions 31 of the necktie holder, while the middle 30 finger actuates the tail portion 26 of the latch bar in disconnecting and removing the holder from the collar button.

Another essential feature of my improved necktie holder is the provision of a plurality 25 of horizontally extending and oppositely positioned prongs 32 which are formed integrally with vertically disposed portions 33 of the outwardly extending arm 16. These prongs 32 are preferably provided with enlarged heads 34 in order to resist the removal or slipping off of a tie band herein-after described, after the same has been 40 mounted in the holder. These portions 34 are offset with respect to the plane of the arms 33 as shown at 33' so as to maintain the band holder in a relatively straight plane. Mounted on these portions 32 is a 45 band 35 which is preferably made of a narrow strip of leather having its outer ends of 50 relatively larger width than the main body portion of the band as shown at 36. The outer ends 36 are provided with two apertures 37 which are adapted to be slipped over the portions 32 on the opposite sides of the 55 holder when the band is mounted on the holder as shown in the dotted line in Fig. 1. In this connection it will be noted that I have provided means whereby the band may 60 be adjusted with respect to the holder by having the apertures 37 engage the two upper and oppositely disposed portions 32 of the holder and in the event this does not raise the tie the required height the band may be inverted and positioned on the upper 65 and oppositely disposed portions, thereby

raising the band with respect to the necktie holder to its highest position. By this arrangement it will readily be seen that I have provided the maximum range of adjustment so that the necktie holder may support ties 70 to accommodate collars of a wide variation with respect to their heights.

Another essential feature of my improved necktie holder is the provision of means whereby the necktie holder in connection 75 with the collar button and neck band of the collar and shirt are clamped together in such a manner that they are secured in a relatively rigid position with respect to each other. This mechanism comprises a 80 forked member 38 having an eye formed at its upper end as shown at 39. The forked member 38 is provided with a vertically extending slot 40 which is adapted to slidingly engage the shank 23 of the collar button. 85 Pivottally mounted in the eye 39 of the forked member 38 by means of a pin 41 is a cam member 42. The cam member 42 is provided with an eccentric cam 43 and a lever 44. When it is desired to clamp the 90 holder in a relatively fixed position with respect to the collar button and neck bands of the collar and shirt the forked member is positioned so that the vertical slot 40 engages the shank 23 of the collar button and the lever arm 44 of the cam member 42 is held at substantially right angles with respect to the plane of the forked member 38 or in the position shown in the dotted lines 95 in Fig. 4. In this position the lower end of the forked member engages the front portion 17 of the necktie holder and an intermediate portion of the forked member engages the underside of the head 23' of the collar button and when in this position the 100 lever is swung to the position shown in full lines in Fig. 4 in which the lever contacts with the top of the collar button as shown at 45. By reason of the relative position of the cam 43 to the lever 44 the camming member 42 is locked in this position because the pivot of the camming member has past the dead center. It will also be noted that by 105 reason of the camming action of the member 42 that the necktie holder and its associated parts, as shown in Fig. 4, are rigidly clamped 110 against displacement from each other. 115

From the above description it will be seen that I have provided a generally improved necktie holder and one which can be readily mounted or removed from the collar button by one hand of the operator, in that the holder may be grasped by the thumb and first finger while the latch bar is actuated by the middle finger. It will further be noted that I have provided an improved clamping device which is particularly adapted for use in connection with soft collars of the high type. In this type of collar this clamping member rigidly secures the parts as well as 120 125 130

the tie and collar in position and prevents their displacement.

While in the above specification I have described one embodiment which my invention 5 may assume in practice it will of course be understood that the same is capable of modification and that modification may be made without departing from the spirit and scope of my invention as expressed in the following 10 claims.

What I claim as my invention and desire to secure by Letters Patent is:

1. A necktie holder comprising a main body portion, arms extending outwardly 15 from said main body portion, laterally projecting prongs extending outwardly from said arms, and a tie supporting band engageable with said prongs for supporting a tie thereon.
- 20 2. A necktie holder comprising a main body portion, arms extending outwardly from said main body portion, a plurality of oppositely disposed projecting prongs extending outwardly from said arms, and a tie supporting band engageable with said prongs for supporting a tie thereon.
3. A necktie holder comprising a main body portion, arms extending outwardly 25 from said main body portion, laterally projecting prongs extending outwardly from said arms, said prongs being offset with respect to the plane of said main body portion, and a tie supporting band mounted on said prongs for supporting a tie thereon.
- 30 4. A necktie holder comprising a main body portion, arms extending outwardly from said main body portion, horizontally projecting prongs formed integrally with said arms, a tie supporting band mounted on said prongs, a latch bar pivotally mounted on said holder for detachably securing said holder to a collar button, and means whereby said holder may be firmly gripped, and a latch bar actuated by one hand of the operator for removing the tie holder from 45 the collar button.
5. A necktie holder comprising a main body portion, arms extending outwardly from said main body portion, horizontally 50 projecting prongs formed integrally with said arms, a tie supporting band mounted on said prongs, a latch bar pivotally mounted on said holder for detachably securing said holder to a collar button, and means extend-

ing forwardly from said holder whereby 55 said holder may be firmly gripped for removing the holder from the collar button.

6. A necktie holder comprising a main body portion, arms extending outwardly from said main body portion, horizontally 60 projecting prongs formed integrally with said arms, a tie supporting band mounted on said prongs, a latch bar pivotally mounted on said holder for detachably securing said holder to a collar button, and rolled 65 portions formed integrally with the holder whereby said holder may be firmly gripped for removing the holder from the collar button.

7. In combination with a necktie holder 70 of a collar button therefor, a collar secured to a neck band by said button, a tie supporting band mounted on said holder, and camming means for securing said holder and button from relative movement with respect 75 to said collar and neck band.

8. In combination with a necktie holder of a collar button therefor, a collar secured to a neck band by said button, a tie supporting band mounted on said holder, and separate 80 and independent means for securing said holder and button from relative movement with respect to said collar and neck band.

9. In combination with a necktie holder of a collar button therefor, a collar secured to 85 a neck band by said button, a tie supporting band mounted on said holder, and detachable means mounted on said collar button for securing said holder and button from relative movement with respect to said collar and neck band.

10. A necktie holder comprising a main body portion, arms extending outwardly from said main body portion, horizontally projecting prongs formed integrally with 95 said arms, a tie supporting band mounted on said prongs, a latch bar pivotally mounted on said holder for detachably securing said holder to a collar button, and means whereby said holder may be firmly gripped, and 100 means formed integrally with and extending forwardly from said latch bar whereby said latch bar may be actuated to remove said holder from said collar button.

In testimony whereof I have signed my 105 name to this specification, on this 11th day of September, A. D. 1924.

PETER L. MARKEY.
